UNITED STATES PATENT OFFICE.

BURTON A. VANDY, OF ROCHESTER, NEW YORK, ASSIGNOR TO SARAH VANDY, OF ROCHESTER, NEW YORK.

SUPPORT FOR ELECTRICAL FIXTURES.

Application filed March 27, 1922. Serial No. 546,951.

To all whom it may concern:

Be it known that I, BURTON A. VANDY, a citizen of the United States, and resident of Rochester, in the county of Monroe and 5 State of New York, have invented certain new and useful Improvements in Supports for Electrical Fixtures, of which the following is a specification.

The present invention relates to supports 10 for electrical fixtures and an object thereof is to provide an improved adjustable bridge adapted to be secured within a ceiling to be supported by two joists. Another object of the invention is to provide a bridge with 15 position-defining devices which will so locate the bridge member on the joists that the fixture support on the bridge will be in proper position with reference to the laths and the plaster of the ceiling. Still 20 another object of the invention is to provide a bridge which may be inexpensively made from sheet material and will have sufficient strength to support the electrical fixtures on the bridge in such a 25 manner that the latter may be adjusted and the securing means will also act to prevent a separation of the members of the bridge. A further object of the invention is to provide a loom holder which will support, in 30 proper position in a ceiling, the looms through which the conductors pass through the ceiling. A still further object of the invention is to provide a loom holder which will also act as a support for the laths 35 meeting such loom holder.

To these and other ends, the invention consists of certain parts and combinations of parts, all of which will be hereinafter described, the novel features being pointed 40 out in the appended claims.

In the drawings:

Fig. 1 is a view in side elevation showing the invention mounted in a ceiling, a fragment of which is shown in section;

45 Fig. 2 is a section on the line 2—2, Fig. 1;

Fig. 3 is a section on the line 3—3, Fig. 1;

Fig. 4 shows the supporting bridge secured so as to support a deep outlet box;

50 Fig. 5 shows the supporting bridge adjusted to support a shallow outlet box;

Fig. 6 is a perspective view of one of the members of the bridge;

Fig. 7 is a section on the line 7—7, Fig. 4; and

55 Fig. 8 is a section on the line 8—8, Fig. 4.

In the illustrated embodiment of the invention there is employed a supporting bridge adapted to be secured to two joists 1 in order to extend between them. This bridge is formed of two members 2 and 3, both, in this instance, made from sheet metal bent into channel form, one being received within the other, their channel faces being opposed. The outer member has preferably at its inner end two lugs 4 bent inwardly over the outer face of the inner member to confine the inner member against lateral displacement at this point. Each member of the bridge has at the outer end thereof an anchoring means for abutment with and adapted to be secured to the joists 1. In this instance, the abutting and anchoring means is provided with positioning means for cooperating with the lower edges of the joists in order to determine the horizontal position of the bridge. This result is secured, in this instance, by providing each of the members 2 and 3 with two lugs 5 and 6, the former being shorter than the other and both being formed by extending the side walls of the two members beyond the bottom of the channel and below said extended positions at right angles. The edges 5^a and 6^a of these two pieces form the positioning means, the edges 5^a on the two members of the bridge being situated at an equal distance from the longitudinal axis of the bridge, the edges 6^a on the two members being likewise positioned. These edges are adapted to be brought into alinement with the under edge of the joists 1 for defining the horizontal position of the bridge.

There may be associated with the bridge, a loom holder 7, which has an externally threaded projection 8 or other means through which any suitable fixture may be attached. This loom holder is preferably supported from the bridge through an inverted U shaped securing device 9, the arms of which lie in close relation to the opposite sides of the bridge and depend below the latter. Between these depending arms, a reduced portion 10 on an upwardly projecting portion of the loom holder 7 is extended, being held in this position by a bolt 11, the upper end of the loom holder abutting the under side of the bridge. The loom holder is elongated transversely of the bridge and on opposite sides of the upward extension is provided with openings 12.

through which the looms 13 are passed, these looms serving as non-conducting coverings for the conductors 14 extending from insulators 15 secured to the opposed faces 5 of the joists 1. On opposite sides of the line formed by the two openings through which the conductor looms 13 pass, the loom holder 7 is provided with two seats 16 which form rests for the laths 17, the vertical height of the loom holder being so proportioned to the lengths of the arms 5 that the seats 6 will be horizontally aligned with the under-surfaces of the laths 17 secured to the joists 1. The thickness of the 10 loom holder below the seat 16 is substantially equal to the thickness of the plaster applied to the laths so that the under face of the loom holder with the exception of the fixture anchoring lug 8 will lie flush 15 with the face of the plaster.

The bridge may also be employed for supporting the ordinary commercial outlet box, a deep form of which is illustrated in Fig. 4 and a shallow form of which is 20 illustrated in Fig. 5, both being indicated at 18. When an outlet box is used, the securing means for the same may be in the form of an inverted U shaped member 9^a having outwardly turned ends 9^b which by 25 bolts 10^b are secured to the outlet box and also to a fixture anchoring member 19 of known construction arranged within the box.

From the foregoing it will be seen that 30 there has been provided a bridge adapted to be supported by the two joists and adjustable to correspond to the distance between said joists. This bridge is formed by two members, one received within the other and 35 preferably both of channel formation with their channel faces opposed. At opposite ends of the bridge, anchoring and abutment means is provided which has thereon positioning means for positioning the bridge in 40 different horizontal positions with reference to the lower edges of the joists. The means which secures the part to be suspended from the bridge also acts to hold the two members of the bridge together, being preferably in the form of an inverted U shaped member having its ends detachably secured 45 to the part to be suspended. A loom holder may be suspended from the bridge by said part and has openings through which the 50 conductor looms pass to the room below the ceiling. On opposite sides of this loom holder rests are provided for the ends of laths secured to the joists. The positioning means are such that these rests may be 55 arranged in proper position for laths se-

cured to the under faces of the joists. The positioning means also properly positions the bridge for outlet boxes of different depths.

What I claim as my invention and desire to secure by Letters Patent is:

1. A support for electrical fixtures comprising a bridge and abutments at opposite ends thereof, each abutment formed with a plurality of position defining devices having ends located at different distances from the longitudinal axis of the bridge.

2. A support for electrical fixtures comprising a bridge and abutments at opposite ends of the bridge each abutment formed by two oppositely extending projections of different lengths, the edge of each projection having ends situated at distances from the longitudinal axis of the bridge equal to the distance that the edge of one of the projections at the opposite ends of the bridge is situated from such axis.

3. A support for electrical fixtures comprising a bridge embodying two members, one of which has a channel in a vertical side and the other of which is received within the channelled member and is flush with the edges of the channel, anchoring abutments at opposite ends of the bridge, and a fixture securing member of inverted U shaped form fitted about the channelled member in abutment with the top and vertical wall thereof and also in abutment with that wall of the other member which is flush with the edges of the channelled member, combined with a fixture secured to the ends of the U shaped member and abutting the under wall of the channelled member.

4. A support for electrical fixtures comprising two channel members one of which is received within the other and the channel in the members being opposed, and anchoring lugs extending outwardly in opposite direction from the side walls of each of the channel members, said lugs at each end having different lengths, and each of said lugs having its outer edge positioned to the same distance from the longitudinal axis of the hanger that a lug in the opposite end has its edge positioned from such axis.

5. In combination with a bridge, an inverted U shaped member fitted about the bridge and having its arms depending below the latter, and a loom holder having a projection extending between said arms and engaging the under side of the bridge, and a bolt passing through the arms and the projection of the loom holder.

BURTON A. VANDY.
